V. HABIB AND L. BENMAYOR,
MACHINE FOR CORRUGATING RADIATOR PLATES,
APPLICATION FILED NOV. 1, 1919.

1,374,298.

Patented Apr. 12, 1921.

UNITED STATES PATENT OFFICE.

VITA HABIB AND LEON BENMAYOR, OF CINCINNATI, OHIO.

MACHINE FOR CORRUGATING RADIATOR-PLATES.

1,374,298.

Specification of Letters Patent. Patented Apr. 12, 1921.

Application filed November 1, 1919. Serial No. 335,070.

To all whom it may concern:

Be it known that we, VITA HABIB and LEON BENMAYOR, citizens of the United States of America, and residents of Cincinnati, in the county of Hamilton and State of Ohio, have invented a new and useful Improvement in Machines for Corrugating Radiator-Plates, of which the following is a specification.

10 Radiator plates vary in width from two inches to six inches or more. The difference in width between adjacent sizes is from one quarter of an inch to one half inch. It has been customary to have separate rolls for 15 corrugating each width of plate. This necessitated not only that a manufacturer should have a stock of all sizes of rolls but that the roll should be completely removed and another one be substituted for every 20 change in width of radiators to be made.

It is the object of our invention to provide means for reducing the stock of rolls and the labor in changing from the making of one size to another size of radiator plates.

25 This and other objects are attained by the means described in the specification and illustrated in the accompanying drawings, in which:—

Figure 1, is a partial plan view of a machine embodying our invention.

Fig. 2, is a side elevation thereof.

Fig. 3, is a sectional view upon an enlarged scale taken upon line 3—3 of Fig. 2.

Fig. 4, is a sectional view taken upon line 35 4—4 of Fig. 3.

Fig. 5, is a detail view of one of the upper disks of the roll.

Fig. 6, is a detail side elevation of one of the guide plates for guiding the metal to 40 the corrugating rolls.

Fig. 7, is a detail end view of the guide mechanism.

The machine embodying our invention comprises a holder A upon which is mounted a rolled strip of brass B, a guiding mechanism C for guiding the strip of metal, a corrugating mechanism D, a spool E upon which the corrugated metal is wound and mechanism for actuating the corrugating 45 mechanism and the winding mechanism.

The holder comprises a standard a, a spindle a' journaled in bearing a² in the standard a and a plate a³ for holding the roll B upon the spindle.

50 The guide comprises a standard c, a guide plate c' which is secured to the standard by

means of arms c² and a movable guide plate c³ which is secured to rods c⁴, c⁵, which are adapted to move through apertures in the fixed guide plate c' and the standard c, 60 which is provided with a set screw c⁶ by means of which the plate c³ may be fixed after it has been adjusted to the proper distance from the fixed plate c'. Plates c', c³, have a front projection upon the end of 65 which are mounted guide fingers c⁷, between which the metal strip is guided between the corrugating rolls.

The corrugating mechanism comprises a standard d which has an elongated opening 70 d' in which is mounted a journal block d², in which is journaled a shaft d³. Journal block d² may be adjusted to different positions in the opening d' by means of adjusting bolts d⁵. In the standard d is journaled a shaft d⁶ upon which the other corrugating roll is mounted. Each corrugating roll comprises inner and outer disks d⁷, d⁸, and a series of inner building disks d⁹. The building disks are made of a thickness equal to the difference in width of the adjacent sizes of radiator plates. Upon each shaft is secured a circular plate d¹⁰ in which are set screws d¹¹ by means of which the inner disk d⁷ is secured in place. The 85 other disks of the roll are clamped between the plate d¹¹ and sleeves d¹² which are mounted upon the shaft and are pressed against the outer ends of the disks by a nut d¹³ which engages screw threads 90 upon the ends of the shafts d³, d⁶ respectively. The periphery of all the disks of the rolls are corrugated. Upon shafts d³, d⁶, are secured intermeshing wheels d¹⁴, d¹⁵.

The spool comprises a spindle e, a plate e' and a reduced end e² about which the strip b is wound. Spindle e is connected by a belt e³ passing over rolls e⁴, e⁵ with a pulley e⁶ which is secured upon a shaft E' which is connected by a drive belt e⁷ with the shaft d³, which may be driven by any suitable mechanism.

In use the roll B is mounted upon the spindle a' and the strip is rolled forward between the fingers c⁷, and guide plates c', c³, which are adjusted a distance apart equal to the width of the plate, by loosening the set screw c⁶. The proper number of building disks are placed between the inner and outer disks d⁷ and d⁸ respectively, to 110 make the width of the rolls correspond to the width of the strip.

The building up of the rolls is a simple operation, being done simply by the removal of the nuts d^{18} , the sleeve d^{12} and the plates d^8 , and the insertion of the proper 5 number of building disks and the replacement of said parts.

Having thus described our invention, what we claim is:—

1. A machine for corrugating automobile 10 radiator plates comprising a guide mechanism and a corrugating mechanism, the guide mechanism consisting of adjustable plates having guide fingers forming parallel ways on the adjustable plates, and means 15 of adjusting and securing them at a distance apart equal to the width of the radiator plate and the corrugating mechanism

comprising corrugating rolls built up of a series of corrugating disks and means for mounting them rotatably adjacent to the 20 guide mechanism.

2. A machine for corrugating automobile 25 radiator plates comprising a corrugating mechanism and a guide mechanism, the corrugating mechanism consisting of rolls built up by a series of corrugating disks, and the guide mechanism consisting of parallel plates adapted to support a width of radiator plate material between them, and means for adjusting the plates. 30

In testimony whereof we have subscribed our names this 15th day of October, 1919.

VITA HABIB.
LEON BENMAYOR.
